FEEDING DEVICE FOR PRESSES

Filed June 30, 1923

Fred S. English, Inventor

By his Attorney
Charles G. Hensley.

Patented Apr. 20, 1926.

UNITED STATES PATENT OFFICE.

FRED S. ENGLISH, OF NEW LONDON, CONNECTICUT.

FEEDING DEVICE FOR PRESSES.

Application filed June 30, 1923. Serial No. 648,846.

To all whom it may concern:

Be it known that I, FRED S. ENGLISH, a citizen of the United States, and a resident of New London, in the county of New London and State of Connecticut, have invented certain new and useful Improvements in Feeding Devices for Presses, of which the following is a specification.

My invention relates to feeding devices for presses and the same is applicable to printing presses of various kinds and also to cutting and creasing presses. Where sheets of stock are fed by hand to a press, if the stock is thick the pile of sheets on the feed table is used up very quickly and it is sometimes necessary to keep a man loading the feed board with stock almost continually in order to keep the feeder supplied with stock. It has been common to provide a feed table long enough to receive two stacks of sheets at a time, one stack from which the feeder takes the sheets and one stack to be moved up into feeding position when the first stack has been used up or fed to the press. As these stacks are sometimes very heavy, sometimes weighing a ton or more, it is difficult to move them manually into feeding position. The object of my invention is to provide power operated means for advancing the stacks into position ready for feeding. I provide manually controlled means for throwing the power means into and out of operation so that the press feeder may advance a new stack into position at any time by power means. Thus, the stack may be moved into position quickly regardless of its weight and without manual labor. The invention therefore consists broadly in providing power means for advancing the stacks into position ready for feeding.

In the drawing forming part of this application:

Figure 1 is a side elevation of part of a printing press showing my invention applied thereto, and

Figure 2 is a plan view thereof.

In the drawing I have shown only such parts of a flat bed press as are necessary to illustrate one application of my invention. Herein I have shown part of the side frame 35 of the press, the impression cylinder 36 to which the feeder feeds the sheets, the platform 32 on which the feeder usually stands, and the feed board bracket 4. I have shown a pile or stack 1 of sheets from

which the feeder takes the sheets, this stack being placed nearest the feeding point; and behind this stack there is a second or reserve stack 2 which is ready to be moved up to the position occupied by stack 1 when the latter has been consumed. The back leaf 5 of the feed table is here shown as horizontally disposed in accordance with former practice.

At 3 I have shown a plurality of endless parallel belts or chains which travel around pulleys or sprockets 6 and 7. These sprockets are mounted on shafts 8 and 9 respectively disposed near opposite ends of the feed table. The sprockets 6, 7 project up through slots 10 and 11 in the feed table so that the upper runs of the belts or chains 3 lay flat on the feed board, and the latter may have a metal surface plate for the chains to travel on if desired.

I have shown girts 12 and 13 for holding the table brackets 4 steady. At 14 is one of the regular shafts of the press and from this I preferably take the power for driving the movable members 3. There is an auxiliary shaft 18 extending across the press at a convenient location, and this shaft is driven continuously from the shaft 14 by means of a chain 16, engaging over the sprockets 15 and 17 arranged on the shafts 14 and 18. There is a second auxiliary shaft 22 extending across the press and this has fixed to it a lever arm 28 which is pivotally connected with a foot treadle 29 which projects up through the platform 32. The treadle has a foot piece 31 and it is normally held in raised position by a compression spring 30 arranged under the member 31.

There is an arm 21 fixed to the shaft 22 and this arm carries a movable shaft 24. There is preferably a duplicate of this arm 21 on the opposite side of the press. There is a friction pulley or gear 20 on the shaft 24, which is adapted to be moved into and out of operative engagement with the gear or friction pulley 19 on the shaft 18. There is a sprocket 25 secured to the shaft 24 and the endless chain 26 travels over this sprocket and over a sprocket 27, for the purpose of transmitting power from the shaft 24 to the shaft 9 and thereby operating the chains or belts 3.

Operation: When the feeder has fed all the sheets from the stack 1 he presses down on the member 31 to depress the treadle 29. This swings over the shaft 24 and throws

the gear 20 into mesh with the gear 19. The power derived from the shaft 14 through the sprockets 15, 17 and chain 16, operates through the gears 19 and 20, and through the sprockets 24, chain 26 and sprocket 27 to drive the chains 3 which support the stack 2. When the latter has advanced to the position previously occupied by the stack 1 the operator releases the treadle and he then proceeds to feed sheets from the newly positioned stack and another stack may then be placed on the chains 3, in the place previously occupied by the stack 2.

Thus, power is employed to move the renewal stacks into position and stacks of any weight may thus be handled quickly without manual labor.

It is obvious that belts may be used in place of chains and that pulleys may be used in place of sprockets, if desired.

Having described my invention, what I claim is:

1. The combination with a press of a feed table, movable means on which a stack of sheets is adapted to rest and to be advanced into feeding position, including endless flexi-

ble members, a gear, and means for operating it from a shaft of the press, a second gear adapted to be thrown into and out of mesh with said first gear, and means operated by said second gear for operating said endless flexible members, and manually operated means for throwing said gears into and out of mesh.

2. The combination with a press, of a feed table having apertures therein, revolvable members protruding into said apertures, endless members traveling over said revolvable members and having one run traveling over the surface of said table to receive a stack of sheets thereon, a revolvable member continuously operated from the press, a second revolvable member and a treadle for throwing it into operation with said continuously revolvable member, and means for transmitting power from said second revolvable member to said endless members for the purpose set forth.

Signed at New London, county of New London and State of Connecticut, this 10 day of April 1923.

FRED S. ENGLISH.
